CLAIM

The ornamental design for a cupcake corer, as shown and described.

DESCRIPTION

FIG. 1 is a front elevational view of a cupcake corer showing my new design;

FIG. 2 is a top plan view thereof;

FIG. 3 is a left side elevational view thereof;

FIG. 4 is a right side elevational view thereof;

FIG. 5 is a bottom plan view thereof;

FIG. 6 is a rear elevational view thereof;

FIG. 7 is a cross-sectional view thereof; taken along line 7-7 of FIG. 1;

FIG. 8 is a perspective view thereof; and,

FIG. 9 is an exploded perspective view thereof.

1 Claim, 9 Drawing Sheets(56)
